FOLDING BOOK RACK

Samuel D. Berlin, Baltimore, Md., assignor to
The Malls Company, Baltimore, Md.

Application July 3, 1956, Serial No. 42,128

Term of patent 7 years

(Cl. D33—2)

Fig.1.

Fig.3.

Fig.2.

Fig.4.

I claim:

The ornamental design for a folding book rack, substantially as shown.
